COOLING LOCOMOTIVE BOILERS

Harold E. Niksch, Chicago, Ill.

Application January 16, 1942, Serial No. 427,029

1 Claim. (Cl. 122—396)

The necessity for rapid and uniform cooling of the boiler preparatory to boiler washing and the difficulty of accomplishing that result have both increased greatly with the coming of the modern high pressure locomotives, such as, for example, the Class S-2, 4-8-4 Type locomotives used by the Chicago, Milwaukee, St. Paul and Pacific Railroad, and disclosed in the Railway Age for April 30, 1938, page 761, and Locomotive Cyclopedias, 1938, pages 215, 216, 217. Those locomotives operate at steam pressure of 285 pounds and have a fire box heating surface of 578 square feet and tubes and flue surface of 4931 square feet. Steam at 285 pounds pressure corresponds to 417½° F.

The customary practice of blowing off the water and steam through the blow-off cock uncovers these great heating surfaces while there is still sufficient heat present to bake on them the unavoidable deposit of suspended matter in the boiler water and thus renders it extremely difficult and costly, if not impossible, to thoroughly clean the inside heating surfaces, which is indispensable to proper maintenance of those high pressure boilers.

The principal object of this invention is to rapidly and substantially uniformly cool large high-pressure boilers while keeping the heating surfaces submerged until the boiler is so thoroughly cooled down that there is no danger of baking the suspended matter on the heating surfaces.

Generally speaking, this is accomplished as follows:

(1) Reduce the steam pressure to, for example, 50 pounds, by blowing off from the top of the boiler;

(2) Introduce cooling water at, for instance, 120° F. through the injector branch pipe until the steam is all killed and the boiler filled, and continue introduction of the water through the branch pipe and out at the top of the boiler until the water leaving the boiler is below steaming temperature, for instance, at 200° F.;

(3) Empty the boiler through the blow-out cock adjacent to the mud ring with the aid of a high capacity pump, and

(4) Remove the top wash-out plugs and begin washing as soon as the crown sheet is uncovered, and continue washing the heating surfaces as rapidly as they are exposed.

It is contemplated that this operation will be carried out with the aid of and in connection with the more or less standard features of hot water boiler washing and filling plants that have

been in common use for many years, the essential features of which may be found in the following: Raymer, No. 757,839 April 19, 1904; Raymer, No. 788,376 April 25, 1905; Gale, No. 831,337 Sept. 18, 1906; Winslow, No. 973,603 Oct. 25, 1910; Miller, No. 1,357,717 Nov. 2, 1919; and Locomotive Cyclopedias, 1922, page 355.

Those plants, in various forms suited to round-houses having a number of radiating stalls and also rectangular engine houses having a number of stalls and a transfer table, are well known. They include a large pipe adapted to be connected with a locomotive for blowing it down and commonly known as the blow-down line, 10 leading to a blow-down tank and associated apparatus by which the heat and water stored in the boiler being blown down is reclaimed. Associated with this system is a washing-out line to supply water for washing out the boiler and 15 either the same or a separate filling water line supplies water for refilling the boiler. In addition, many of the systems include a steam line for heating up the boilers and for bringing them up to steam pressure after being refilled 20 and maintaining them in steamed condition 25 during storage.

The single figure of the drawing shows an embodiment of my invention.

In the interest of simplicity, the drawing omits 30 most of the engine house and hot water washing and filling apparatus and includes only the essential parts shown diagrammatically associated with a diagram of a locomotive boiler. But it will be understood that those features 35 will be readily associated with the various types of hot water boiler washing and filling plants.

In the drawing the locomotive boiler is shown 40 at 10, having a dome 11 fitted with 1½" steam valve 12, adapted to be connected with a drop pipe 13 by flexible connection 14, such as the familiar Barco joint. The drop 13 is equipped with a check valve 15 and is one among several 45 leading to the blow-down line 16, which delivers to a condenser 17 and that, in turn, delivers to a pipe 18 leading into the lower portion of the blow-down tank 19, supplied by a water pipe 20, controlled by a float valve 21.

The sediment in the tank 19 is allowed to settle to the bottom from which it is blown off 50 from time to time and in order to avoid taking the sediment back into the system, water is drawn from the tank 19 through a pipe 22, the intake end of which is held up by a float 23 and the opposite end is swiveled at 24, to a pipe 55 25 leading into a tank 26, which may be for wash

out water or refill water, according to the preference of the engineer designing the system.

Water from the tank 26 is also drawn off through a float suction pipe 27, leading to the supply pipe 28 of a refill pump 29, which delivers through the upright pipe 30 to the line 31, which may be either the wash out or refill line running around the engine house and equipped with drops at the respective stalls, one of which drops 32 is equipped with a hose 33, adapted to be connected with the injector branch pipe 34 of the boiler 10.

The pipe 30 is connected with a pipe 35 for tempering water, the flow of which is controlled by thermostatic valve 36 regulated by thermostatic element 37, which may be adjusted to regulate the temperature of the water in the line 31, in accordance with the wishes of the engineer in charge.

For the purposes of this invention the Y fitting 38 of the injector branch pipe 34 is equipped with a welded nipple 39, which is adapted to receive either the connection 40 of the hose 33 or a threaded wash-out cap, the threads of which are designed to endure numerous connections and disconnections.

The usual drop 41 connected with the blow-down line and fitted with a check valve 42 is, in this instance, connected by the flexible connection 43 with a pipe 44, connected to the exhaust of a centrifugal pump 45, the intake side of which is connected with the blow-off cock 46, adjacent to the mud ring of the locomotive by the flexible connection 47 and a pipe 48. For a locomotive of the class mentioned a 15 H. P. centrifugal pump having the capacity of two hundred (200) gallons per minute is appropriate.

When a locomotive to be serviced has been run into a stall, the procedure with the indicated apparatus according to this invention may be as follows:

(1) Connect the drop 13 from the blow-down line 16 with the 1½" steam valve 12 on the dome of the locomotive, open the valve and reduce the steam pressure to a selected limit, as for example, 50 pounds.

(2) While the first operation is being performed, connect the hose 33 with the nipple 39 of the injector branch pipe 34 and as the reduction of the steam pressure reaches the selected limit, start the flow of cooling water into the boiler through the branch pipe 34. This water will be regulated according to the setting of the thermostatic element 37. Some will prefer one temperature and some another, but approximately 120° F. will be found satisfactory. Continue the flow of this cooling water until the steam is all killed, the boiler is filled and the water has circulated out through the valve 12 until it reaches a temperature below steaming as, for example, 200° F.; stop the flow of water in through the injector branch line;

(3) Connect the pump 45 with the blow-out cock 46 and empty the boiler rapidly, pumping the water through the blow-down line to the blow-down tank 19;

5 (4) As soon as the crown sheet is uncovered remove the top wash-out plugs and start washing the boiler; continue washing the boiler as the heating surfaces are uncovered;

10 (5) When the washing is completed, replace the plugs and immediately fill with heated water. If the work has progressed properly, as indicated, filling water at approximately 120° F. will be found satisfactory. Some engineers however, prefer to use filling water at 180° F. or higher.

15 The arrangement of the wash-out plugs, etc., has been omitted from the drawing and description in the interest of clearness and brevity, but the necessary information can be had from the Locomotive Cyclopedic, 1938, page 410.

20 As indicated above, it is contemplated that the operation described will be carried on at a number of different stalls in an engine house, where the drops, etc., will be substantially as shown in the drawing. A considerable economy, however,

25 can be effected by omitting to install a separate pump 45 for each stall and by mounting such a pump with the necessary flexible connections, etc., on a truck 49, which can be conveniently rolled from one stall to another in use. In large

30 engine houses where several locomotives are to be serviced at the same time a corresponding number of portable pumps will be appropriate. Some engineers will object to step 2 of the above mentioned procedure because the superheaters

35 will be flooded as an incident to filling the boiler and circulating water out through the dome to the blow-down line. To overcome this objection the pump 45 may be connected to the blow-off cock 46 and started in operation after the water

40 level in the boiler has reached a suitable height and before flooding the superheaters. By this means the cooling water will be circulated through the boiler, entering through the branch pipe 34 and leaving through the blow-off cock

45 46. As indicated before the circulation should be kept up until the water leaving the boiler is below steaming temperature, for example, 200° F. although, of course, it may be lower if preferred. Some engineers will incline to favor this modified procedure because of the enhanced circulation over the heating surfaces of the fire box.

What I claim is:

55 In apparatus of the class described, an engine house having locomotive stalls, a blow-down line and a heated water line adjacent to said stalls, means for connecting the top of a locomotive boiler with the blow-down line, means for connecting the branch pipe of the boiler with the heated water line, a pump, and means connecting the pump with the bottom of the boiler and with the blow-down line.

HAROLD E. NIKSCH.
